UNITED STATES PATENT OFFICE.

ANDREW JACKSON FAIR, OF WALNUT COVE, NORTH CAROLINA.

TOBACCO-STEAMER.

SPECIFICATION forming part of Letters Patent No. 605,412, dated June 7, 1898.

Application filed May 4, 1896. Serial No. 590,110. (No model.)

To all whom it may concern:

Be it known that I, ANDREW JACKSON FAIR, a citizen of the United States, residing at Walnut Cove, in the county of Stokes, State 5 of North Carolina, have invented certain new and useful Improvements in Tobacco-Steamers, of which the following is a specification, reference being had therein to the accompanying drawings.

10 My invention relates to a light portable steamer having suitable provision for conveying the steam into the barn and subjecting the tobacco to its action, which keeps it moist and allows it to dry evenly throughout, so that 15 it all dries yellow.

The device can be set up in any desired position and the amount of steam therefrom easily regulated.

Other objects and advantages of the invention will hereinafter appear, and the novel features thereof will be particularly pointed out in the claim.

The invention is clearly illustrated in the accompanying drawings, which, with the letters of reference marked thereon, form part of this specification, and in which—

Figure 1 is a substantially central vertical section through my improved apparatus, showing its manner of use. Fig. 2 is a cross-section on the line 2 2 of Fig. 1, looking downward, and Fig. 3 is a perspective detail on a smaller scale.

Like letters of reference indicate like parts throughout the several views.

35 Referring now to the details of the drawings by letter, A designates a boiler, preferably of sheet metal, of any desired capacity, being preferably in the form of a truncated cone, as shown, and having a suitable top a, 40 in which is a central opening closed by valve or other closure B, made steam-tight, yet removable—that is, capable of being taken off in any suitable manner for the introduction of the water.

45 C are flues, of which there may be any desired number, extending in an inclined direction through the boiler from side to side and communicating at one end with the stack or flue D, through which the products of combustion pass, and at the other end opening into the chamber E, which is formed between the boiler and the inclined wall e, which, to-

gether with the boiler proper, is supported upon the flange or base F, which is designed to be supported from the ground or any other suitable support and extends nearly around the boiler, having an opening f, as seen in Figs. 1 and 3, and within the space inclosed by said ring or flange and beneath the bottom of the boiler is designed to be made a fire of wood or any suitable material.

The boiler may be provided with suitable handles G, whereby the same can be easily moved about from place to place, and also by preference provided with a water-gage H, so that the height of water within the boiler can be readily discerned, it being essential to keep the water within the boiler above the flues, so as to prevent burning of the latter.

The top of the boiler is provided with a 70 nipple I, having a suitable cock or valve J, and to the upper end thereof is designed to be attached a pipe or hose K, which should by preference be of a flexible nature, so that it can be extended to any desired point. 75

In practice the water is placed within the boiler and the fire started beneath the same, the hose being disposed so as to conduct the steam to the desired point, in this instance being shown as extended through an opening 80 l into the barn or building L, within which the tobacco is designed to be suspended or arranged in any suitable or convenient manner. The products of combustion are indicated by the arrows in Fig. 1 passing along 85 the bottom of the chamber up through the chamber E, and thence through the inclined flues C, which, as will be seen, pass through the water within the boiler, and thence out through the stack D into the open air. The 90 steam from the boiler is conveyed through the hose or other connection K into the building, which should be steam-tight, and the moisture permeates the tobacco and causes the more rank or gummy or green leaves to become more like those that are more matured, so that when cured it will be all of a like shade 95 of yellow instead of part green and part yellow. The amount of steam conveyed to the building may be regulated by the cock or valve J. The valve or closure B is of such a nature as to be opened under abnormal pressure of steam, so as to avoid injury to the apparatus. I have found that the steam acts

peculiarly upon tobacco and brings about a chemical action therein, which adds materially to the marketable value of the tobacco and retains therein and enhances the flavor.

5 Modifications in detail may be resorted to without departing from the spirit of the invention or sacrificing any of its advantages.

Having thus described my invention, what I claim as new, and desire to secure by Letters

10 Patent, is—

A tobacco-steamer comprising a vertical water-chamber, a depending casing to support the water-chamber and form a fire-box be-

neath the same, a stack located upon one side of said chamber, a series of diagonally-extending flues in the lower part of said chamber and communicating with the fire-box and stack, and a steam-conducting pipe extending from the upper part of said chamber, substantially as and for the purposes set forth. 15 20

In testimony whereof I affix my signature in presence of two witnesses.

ANDREW JACKSON FAIR.
